HAT RACK

Robert D. Westervelt, 4113 Bryer Place, Peoria, Ill.

Filed Oct. 18, 1963, Ser. No. 77,037

Term of patent 3½ years

(Cl. D33—8)

Fig. 1

Fig. 2

Fig. 3

Fig. 5

Fig. 4

FIG. 1 is a perspective view of a hat rack showing my design wherein screw eyes are applied to the rearwardly extending arms as wall attaching means;

FIG. 2 is a side elevational view;

FIG. 3 is an end elevational view;

FIG. 4 is a perspective view of the hat rack of FIG. 1 wherein a hook bracket suspension means is employed; and

FIG. 5 is a side elevational view thereof.

I claim:

The ornamental design for a hat rack, as shown and described.
